UNITED STATES PATENT OFFICE.

HUGO BOELTER, OF TOLEDO, OHIO.

ADJUSTABLE PLATFORM.

SPECIFICATION forming part of Letters Patent No. 790,341, dated May 23, 1905.

Application filed October 10, 1904. Serial No. 227,897.

To all whom it may concern.

Be it known that I, HUGO BOELTER, a citizen of the United States, residing at Toledo, in the county of Lucas and State of Ohio, have 5 invented a new and useful Improvement in Adjustable Platforms, of which the following is a specification.

This invention relates to a platform upon which a model stands, the object of the invention being an improvement in means for fitting ladies' skirts. The platform has its upper peripheral portion in the form of a vertically-movable ring which may be raised to the desired height. The skirt falls over the 15 ring, and the lower edge of the skirt is held against the periphery of the ring and a suitable mark made. The exact length of the skirt as when in use can thus be accurately determined.

20 The invention consists in a platform comprising an essentially stationary center and a vertically-movable periphery.

The invention further consists in the novel features of construction and combination of 25 parts hereinafter described, pointed out in the claims, and shown in the accompanying drawings, in which—

Figure 1 is a side elevation of my preferred form. Fig. 2 is a plan view of the same. 30 Fig. 3 is a detail sectional view showing the ring elevated. Fig. 4 is a modified form of construction, the movable parts being shown in elevation and the platform and ring in section. Fig. 5 is a sectional plan view of the 35 construction shown in Fig. 4, the section being taken immediately below the platform. Fig. 6 is a detail view showing a portion of the modified form with the ring lifted above the plane of the platform.

40 In the drawings, A represents a circular platform having its periphery cut away and a vertically-movable ring A' resting in the cut-out portion. The platform A is supported by the legs A², and beneath the platform is

45 suspended on a suitable shaft inclosed in a casing C a rotatable disk B. Arms B' are pivoted at their outer ends to the legs A², and their inner ends rest freely upon the disk B. The arms B' are slotted longitudinally, as shown

50 at B², and a pin B³ is arranged on the disk B

and engages the slot B², there being one pin for each arm. To the inner free ends of the arms B' are pivoted the inner ends of elastic steel spring-strips E. These strips pass under and upwardly on the outer face of rollers D, 55 being held in engagement with the rollers D by smaller rollers D'. The strips E pass freely through the marginal portion of the platform A and are connected to the ring A' and are sufficiently stiff to lift and hold the 60 ring A' vertically above the plane of the platform A. A handle F is connected at its inner end to the disk B, and by means of the same the disk will be rotated. During such rotation the pins B³ in engagement with the 65 slots B² of the arms B' will swing the arms on their pivot-points, and this movement will be transmitted to the strips E in the form of a positive movement inward or outward, owing to the direction of rotation of the disk, 70 and the ring will be elevated or lowered.

In Figs. 4, 5, and 6 I have shown a modification in the manner of actuating the ring-supports. The construction of the platform and ring is unchanged; but a square casing C' 75 depends below the center of the platform A and contains a central shaft C², and the bottom of the casing C' has on one side a lateral extension C³. The sides of the casing are slotted, and working through the same are 80 four rack-bars J, arranged in pairs, the pairs being at right angles to each other. In the square space formed within the casing C', between the rack-bars J, is arranged a spur-gear K', carried by a sleeve K, fitted upon the 85 shaft C². The gear K' meshes with the rack-bars J, and each bar of a pair is thereby moved in a direction opposite the bar parallel to it, the bars constituting a pair being arranged on opposite sides of the spur-gear K'. 90 To the outer ends of the bars J are connected steel strips J', corresponding in every way to the strips E. The extension C³ of the bottom of the casing C' carries a spur-gear L. A handle M is connected to the sleeve K and 95 carries a rack-segment L', which meshes with the spur-gear L and acts as a controller for the spur-gear K' and racks J. Adjacent the outer end of the handle M is arranged a rack or smooth segment M', depending from the 100

under side of the platform A and upon which the handle rests and moves. A hand-grasp M² is bifurcated at its inner end and the bifurcation fitted over the outer end portion of the handle M and pivoted thereto. When the handle has been moved into any desired position on the segment M', the hand-grasp can be turned downward at right angles to the handle M, and the inner end of the hand-grasp 5 M² will engage the under face of the platform A and serve to hold the handle in its adjusted position. A scale O is laid out upon the periphery of the platform A below the cut-out portion, and the hand-grasp not only 10 serves as a convenient means for moving the handle M and as a lock, but also as a pointer indicating upon the scale when turned at right angles to the handle M the exact height in inches or fractions thereof to which the 15 ring A' has been elevated with respect to its normal position on the platform, and it will be noted that normally the upper edge of the ring is flush with the top of the platform A. It will be understood that the scale, as shown 20 at O, is placed on both forms of the device, as the platform is the same in construction, and in Figs. 1 and 2 the upwardly-curved end F' of the handle F serves as the pointer on the scale.

Having thus fully described my invention, 30 what I claim as new, and desire to secure by Letters Patent, is—

1. A device of the kind described comprising a stationary platform having its marginal portion cut away adjacent the upper face of the platform, a ring adapted to rest in said cut-out portion, and means for raising the ring above the platform. 35

2. A device of the kind described comprising a platform, a vertically-movable ring carried by the platform, means for elevating the ring, a handle adapted to actuate said means, and a scale laid off upon the side of the platform, the outer end portion of the handle being adjacent the scale. 40

3. A device of the kind described comprising a circular platform, a ring thereon, legs supporting the platform, rollers carried by the sides of the supporting-legs, elastic steel strips connected at one end to the ring and guided by the said rollers, and means arranged below the platform for reciprocating the strips. 45

HUGO BOELTER.
